(57) **CLAIM**

The ornamental design for a display panel or screen with
animated graphical user interface, as shown and described.

DESCRIPTION

The patent or application file contains at least one drawing
executed in color. Copies of this patent or patent application
publication with color drawing(s) will be provided by the
Office upon request and payment of the necessary fee.

FIG. 1 is a front view of a first embodiment of a display
panel or screen with a first image of a graphical user
interface showing our new design;

FIG. 2 is a second image thereof;

FIG. 3 is a third image thereof; and

FIG. 4 is a fourth image thereof

FIG. 5 is a front view of a second embodiment of a display
panel or screen with a first image of a graphical user
interface showing our new design;

FIG. 6 is a second image thereof;

FIG. 7 is a third image thereof; and,

FIG. 8 is a fourth image thereof.

The appearance of the image transitions sequentially
between FIGS. 1-4 and FIGS. 5-8 respectively. The process
or period in which an image transitions to another forms no
part of the claimed design.

The outermost broken lines illustrate a display panel or
screen and form no part of the claimed design. The dot-dash
broken lines illustrate the boundary of the claimed design
and form no part of the claimed design. The remaining
